UNITED STATES PATENT OFFICE.

DAVID F. S. COOK, OF KOKOMO, INDIANA.

VENDING-MACHINE.

SPECIFICATION forming part of Letters Patent No. 516,675, dated March 20, 1894.

Application filed July 3, 1893. Serial No. 479,460. (No model.)

To all whom it may concern:

Be it known that I, DAVID F. S. COOK, a citizen of the United States, residing at Kokomo, county of Howard, and State of Indiana, have invented new and useful Improvements in Postal-Card, Envelope, and Postage-Stamp Vending Machines, of which the following is a specification.

My invention relates to new and useful improvements in an apparatus for vending envelopes, postal cards, and postage stamps, and consists in mechanism controlled by the insertion of a coin or coins which operate the mechanism for discharging the envelope, postal card, or postage stamp, and will be hereinafter more fully set forth.

The object of my invention is to provide an apparatus that will operate to deliver a postal card, stamp, or envelope to a purchaser without the intervention of an attendant or clerk. I attain this object by means of the apparatus illustrated in the accompanying drawings in which similar numbers and letters of reference designate like parts throughout the several views in which—

Figure 1 is a side sectional elevation of the apparatus showing the mechanism thereof. Fig. 2. is a front sectional elevation of the same. Fig. 3. is a sectional plan of the same. Fig. 4. is a perspective detail broken view of the rear racks of the operating mechanism. Fig. 5. is a perspective detail sectional view of the conducting tubes. Fig. 6 is a broken view of a portion of the front of the apparatus showing the slots wherein the coins are inserted, and the operating lever of the apparatus. Fig. 7. is a perspective view of the rams or plungers for pushing the coins along the conducting tube and against the operating racks. Fig. 8. is a detail sectional view of a broken off portion of one of the vertical shafts showing the yielding or flexible torsional joint; and Fig. 9. is a view of the slats of the envelope rack and showing the manner of connecting their ends in plan and elevation.

The mechanism of the apparatus is inclosed in a casing 1, which is subdivided into several interior compartments. The compartment 2, incloses the operating mechanism, the compartment 3, the coins, the compartment 4, the postal card carrier racks, and the compartment 5, the envelope carrier racks.

The postage stamp mechanism is composed of a spool or reel 6 journaled in suitable supporting bearings 7, which are firmly secured to the supporting bar 8, firmly secured to the sides of the casing, 1, of the machine. On the spool or reel 6, is wound a continuous ribbon or strip of postage stamps, which has been formed by tearing a sheet of postage stamps into long strips, the ends of each of the strips being united or connected by a blank piece of paper and in such a manner as to form equal spaces between the punctures of all the sheet or strip. This continuous ribbon of postage stamps has its delivery end passed over the top of the periphery of the stamp wheel 9 and between the bite of said wheel and its holding or pressure drum 9^a, and in such a manner as to cause the holding pins 10, which are spaced at regular intervals across the face of and around the periphery of the wheel 9, to properly engage or register with the punctures formed between the stamps. The holding drum 9^a, has a series of peripheral grooves formed around its face and at such a distance apart as to permit the pins 10 of the stamp wheel 9, to pass or clear. The stamp wheel 9 is journaled in suitable bearings 11, formed integral with the casing of the apparatus. One end of the journal 12 of the stamp wheel 9, is extended beyond its bearing 11, and has the detent or ratchet wheel 13, the throw-out cam wheel 14, and the bevel wheel 15, firmly secured thereon. The pawls 16, and 17, are adapted to alternately engage the teeth 18, at the top and bottom sides of the wheel 13, and are pivoted at their opposite ends to the throw-out lever 19. The throw-out lever 19, is pivoted on its supporting bracket 20, firmly secured on the cross stay or bar 8, and has its lower swinging end provided with a roller 21, with which the cam 22, formed on the top of the rack bar 23, contacts to swing said lever 19, backwardly to move the throw out toe 24, against the pawl 16, to disengage it from one of the bottom teeth 18, and to permit the stamp wheel to rotate till the pawl 17, engages the next consecutive tooth 18. The pawls 16, and 17, are provided with a tension spring 25, which moves them toward each other and into contact with the teeth of the detent wheel. In order that the pawl 17, may

not drop into engagement before the detent wheel 13 has rotated sufficiently to discharge one stamp, I provide the roller 26, which is journaled in the fork holder 27, which is adapted to slide longitudinally in the socket 28, formed on the top edge of the pawl 17, which sliding piece is surrounded by a coil spring 29, between its roller and the end of said socket which permits the roller to slightly recede or yield when suddenly dropped on the cam retaining teeth 30, formed on the cam wheel 14. The stamp wheel is rotated by means of its bevel wheel 15 meshing with the bevel wheel 31, on the shaft 32, said shaft 10 journaled in suitable bearings 33, and 34, and having the bevel wheel 35 meshing with the bevel wheel 36, loosely mounted on the vertical shaft 37, which shaft is journaled in its bearing 38, secured on the cross-bar 39, and 15 journaled at its bottom end to the floor of the compartment 2. The top end of the driving shaft 37, is surrounded with a coil spring 40, which is secured at its top end to the top of said shaft and at its bottom end to the bevel wheel 36, thereby forming a yielding connection or coupling by which means the said shaft is permitted to rotate to some extent when either of the pawls 16, or 17, engage the detent teeth, 18, to stop the rotation of said 20 shaft, 32, and the wheels positively connected thereto. On the lower end of the shaft 37, is firmly secured the ratchet-wheel 41, with which the pawl 42, pivoted on the wheel 43, engages, which latter wheel works loosely on 25 said shaft and only operates to rotate said shaft 37, when rotated in the direction of the arrows as shown in Fig. 3.

The envelope operating shaft 44, and the postal card shaft 45, are operated by mechanism substantially similar in construction and operation to the motion of the stamp mechanism already described, and each of the operating parts of the one or right hand side corresponds with each of the similar parts of 40 the opposite or left-hand side so that the addition of a prime added to the designating figures on the one side will suffice to designate the parts corresponding with the parts represented on the opposite side by plain 45 numbers. The shaft 44, as is also the similarly operated shaft 45, is rotated by means of the wheels 46, and 46' mounted loosely on said shafts and provided with the pawls 47, and 47' which engage the ratchets 48, and 48' 50 securely fastened on the lower sections of said shafts 44, and 45. The lower sections of these shafts 44, and 45, are formed with sockets adapted to receive the reduced lower ends of the top sections of said shafts, each of said 55 sections being surrounded with a coil-spring 44^a, and 45^a, (similar to the spring 40,) and have their top and bottom ends secured in any suitable manner to said top and bottom sections of said shafts to form a yielding connection or coupling. On the bottom ends of 60 the top sections of said shafts are firmly secured the bevel wheels 49, and 49' meshing

with the bevel-wheels 50, and 50' to which latter wheels are firmly secured the detent wheels 51, and 51' and the cam toothed wheels 7c 52, and 52' all of each set of wheels rotate together on the pins 53, supported by suitable hangers 54, and 54'. The pawls 55, and 56, are adapted to alternately engage the teeth 57, of the ratchet detent 51, and are provided 75 with the tension spring 58, by which they are operated to move toward each other to engage said detent wheel or ratchet when released. Pawls as 55, and 56, are pivoted to the throw-out levers 59, and 59', which latter 80 levers are pivoted on their supporting bearings 54, and 54' and have their throw-out toes 60, adapted to raise and to lower the pawls 55, and 56, out of engagement; said levers having their lower swinging ends forked to pivotally 85 receive the cam rollers 61, and 61' with which the cams 62, and 62', formed on the top edges of the racks 63, and 63', contact to swing said levers backwardly to move the throw-out toe 60, against the pawl 55, to disengage it from 90 one of the top detents of the wheel 51, and permit a partial rotation of the shafts 44, and 45, till either the lower pawls 56, engages its next consecutive tooth. In order that the pawl 56, does not engage before the detent 95 wheel 51, has rotated a distance equal to the space from the center of one tooth to the center of the next consecutive tooth I provide the roller 64 pivoted in the fork piece 65, which latter piece is adapted to slide longitudinally 100 in its socket 66, formed on the end of said pawl 56, and is surrounded with a coil spring 67, extending between its roller and the socket of the pawl and by which the roller 64, is permitted to recede in the same manner and under the same conditions as the roller of the pawl 17, previously described. 105

On the top ends of the shafts 44, and 45, are firmly secured the bevel wheels 67, and 67', which mesh with the bevel wheels 68 and 68' 110 firmly secured on the shafts 69, and 69' which are journaled in the side walls of the partitions 4, and 5, and in the center bearing 70.

In order that the shafts 44, and 45, be permitted to rotate in one direction only, I provide the ratchet wheels 71, and 71' firmly secured on said shafts and having their teeth adapted to engage the pawls 72, and 72' only when rotated in a direction opposite to that which they should move. 115

In each of the compartments 4, and 5, are inclosed endless chain-racks between the leaves or vanes 73, and 73' of which are inserted postal cards or envelopes one to each rack or division. The leaves or vanes 73, and 73' are secured in any suitable manner to their beveled slats 74, (see Fig. 1,) the ends of which are rounded or trunnion formed and pivotally connected to the chain links 75, to form an endless chain, said beveled bottom edges of said slats adapted to work in the toothed wheels 76, by which they are traversed and in the carrier wheels 77, at the front end of the interior of the machine. It 120 125 130

will be readily seen that when the vane or slat *a*, is moved to the position occupied by the slat *b*, the postal card or envelope contained therein will fall by gravity into the delivery slot 78' onto the table 79. The racks 23, 63, and 63' are formed alike and are provided with the tongue-pieces 80, all of which are adapted to accurately fit and to slide longitudinally in their guide tubes 81. Each of the tongues 80, are slotted midway between their top and bottom edges for a portion of their lengths for the purpose of permitting the plunger 82, to move the full extent of its stroke without contacting the plunger 80 to move and to operate the mechanism connected thereto as in such cases where a person attempts to operate the mechanism without inserting the proper coin or coins. The tubes 81, are also provided with horizontal slots 81^a see Fig. 5, which intersect the portion of their vertical slots, and in which the plungers 82, slide, each of which plungers is connected by a crosshead 83, which has the toothed rack 84, formed thereon and the teeth 25 of which mesh with segmental end 85, of the operating lever 86. The lever 86, is pivoted at or near its center on the bracket 87, secured to the casing of the machine. Between the handle and the pivotal point of the lever 30, is the rack or segment 88, secured to a suitable supporting bracket on the casing of the machine; said segment having its front end 89, raised higher than the top of its ratchet teeth and is provided for the purpose 35 of raising the pawl 90, out of gear when the said lever 86, has reached the limit of its stroke. The segment is also provided with the cam 91, formed on its opposite end and is for the purpose of throwing said pawl into 40 engaging position in which position it is held by its retaining spring 92, when the said operating lever has receded into its normal position. In order that the operating lever 86, may, when having completed its stroke, automatically return to its normal position, I 45 provide the tension spring 93, secured to said lever and to a suitable retaining hook secured to the casing of the machine. The coin conducting tubes 94, connect with the 50 vertical slots formed in the conducting tubes 81, and are of the width and depth sufficient to permit the coins as pennies, to freely pass through.

In the under sides of the tubes 81, between 55 the plungers or rams 82, and the rack's tongues 80, a recess is formed which is of a breadth equal to that of the vertical slot formed therein. In this recess or slot is pivoted a gate or vibratory bridge 95, which is held in the position shown in the drawings by the spring 96, (see Fig. 1,) thus it will be readily understood that when the coin or coins contact with the top portion of said pivotal bridge the latter turns to close said recess formed in the bottom side of the tube 81, and permits said coins to contact the end of the operating

tongues 80, of the operating racks by which the mechanism is put in motion.

The operation of the machine is as follows:—To obtain a postage stamp, valued at two cents, two pennies or cents are inserted into the central or postage stamp tube, from the outside of the machine (as shown in Figs. 1, 3, and 6.) and said pennies fall by gravity into the tube 81, just in advance of the plunger 82, and in front of the bridge 95. The operating lever 86, is now pulled toward the operator till it is moved to the end of its stroke till the plungers 82 have moved forward sufficiently to cause the coins to contact and to press against the tongues of plunger 23, which causes its rack to gear or mesh with the driving wheel 43, to turn the shaft 37 against the resisting tension of the spring 40. Simultaneous with this movement of the shaft 37, or nearly so the cam 22, contacts with the roller 21, to swing the lever 19, backwardly to cause the toe 24, to contact with the pawl 16, to disengage it from its detent tooth 18 and to permit the stamp wheel to rotate the distance 90 from the center of one tooth to the center of the next consecutive tooth, that is, the length of a single postage stamp. Immediately the lever 86, is released and permitted to recede into its normal position the plunger 82, recedes and the rack springs 8, force the racks 22, backward to cause the plungers 80, to recede and to push the coins back against the bridge 95, which immediately opens when the end of the ram or plunger 82, passes its edge thereby intercepting the further movement of the coins in the tube 81, and causing them to drop into the chamber 3, through the recess under the tube 81. It will be seen that the rack 23, receded into its normal position, its cam 22, permits the lever 19, to swing backward to its original position thereby disengaging the pawl 17, and causing the pawl 16, to engage with its tooth 18, before the pawl 17 is fully disengaged thereby locking the ratchet or detent wheel and preventing any further rotation of the stamp wheel 9, till such times as the necessary coins have been inserted in the slot to repeat the operation. The mechanisms for vending postal cards and envelopes are similar in their operation to the mechanism just explained, with the exception of the discharging and carrying racks, which have been already described and will not require any further explanation.

Having thus fully described the construction and operation of my invention, what I claim as new and useful, and desire to cover by Letters Patent of the United States therefore, is—

1. In a stamp vending machine, a stamp wheel having a series of barbs or pins projecting from its peripheral surface, said pins arranged in single rows across the face of and divided or spaced with equal spaces between said rows round said peripheral surface, and a compressing drum having peripheral grooves

- 4
- adapted to register with the pins of the said stamp wheel, of a ratchet wheel adapted to rotate with said barbed wheel, pawls on opposite sides of said ratchet wheel, a cam wheel between said pawls and suitable means whereby the said pawls and the said cam are operated to cause the said pawls to alternately engage and disengage their ratchet wheel to permit a partial rotation of said stamp wheel, substantially as and for the purpose set forth. 5
2. In a stamp vending machine, the combination with a stamp wheel and its retaining roll, of a ratchet wheel, a cam wheel having a series of cams equal in number to the teeth of said ratchet wheel said cam wheel adapted to turn with said ratchet wheel, pawls on opposite sides of said ratchet wheel a yielding cam roller on one of said pawls and a swinging lever adapted to disengage said pawls, 15 and suitable means for rotating said ratchet wheel and operating said swinging lever, substantially as set forth. 20
3. In a stamp or other vending machine, the combination with a rotative stamp wheel, and its retaining roll, of a ratchet wheel a cam wheel adapted to rotate with said ratchet wheel and having a series of cam teeth equal in number to the teeth of said ratchet wheel, pawls on opposite sides of said ratchet wheel, 25 a yielding cam roller on the end of one of said pawls and a swing-lever adapted to disengage said pawls, a reciprocating rack having a cam adapted to contact the swinging end of said lever, a wheel engaging said rack, a shaft 30 adapted to turn in one direction only with said wheel, a wheel loosely mounted on said shaft and driving (directly or through intermediate gearing) said ratchet and its cam wheel, a spring secured on said driving shaft, 35 and having one secured to the latter driving wheel, a coin conducting tube wherein the operating tongue and rack plunger slide longitudinally and suitable means whereby the

coins are introduced between the said tongue and plunger, substantially as set forth. 45

4. In a vending machine, the combination with a coin conducting tube having longitudinal coin conducting slots formed therein, plungers adapted to slide in said slots, a lower recess formed in the under side of said conducting tube intermediate between the ends of said tube, a bridge pivoted over said opening and adapted to close the same when moved in one direction only, substantially as set forth. 50

5. In an envelope vending machine, an endless or continuous rack composed of a series of transverse slats having their under edges or engaging faces wedge formed, said slats having their ends pivoted at their ends to 60 endless carrying chains, wings or vanes secured on the upper or outer edges of said slats, pulleys having triangular grooves extending across their bearing faces and equally pitched or divided round their peripheries 65 and adapted to receive and to accurately fit the wedge formed edges of said slats, and suitable means for rotating said pulleys to traverse said rack, substantially as and for the purpose set forth. 70

6. In a vending machine, a pivotal operating lever having a segmental toothed end and a handle end, a pawl pivoted on said lever, a pawl spring contacting said pawl, a toothed segment with which said pawl engages, cams formed on the ends of said segment, adapted to throw said pawls into or out of engagement with the teeth of said segment, substantially as and for the purpose set forth. 75

In testimony whereof I have hereunto set 8c my hand in the presence of two subscribing witnesses.

DAVID F. S. COOK.
